DESIGN FOR A FINGER RING

Lucien S. Burri, New York, N. Y.

Application February 24, 1939, Serial No. 83,177

Term of patent 14 years

To all whom it may concern:

Be it known that I, Lucien S. Burri, a citizen of the United States, residing at 3133 Rochambeau Avenue, Bronx, in the county of New York and State of New York, have invented a new, original, and ornamental Design for Finger Rings, of which the following is a specification, reference being had to the accompanying drawing, forming part thereof.

Fig. 1 is a side elevation of one side of the ring;

Fig. 2 is a similar view of the other side;

Fig. 3 is a developed plan view of the face of

the ring commencing at 3—3 of Fig. 1 and progressing in a clockwise direction;

Fig. 4 is a plan view of the face of the ring as seen from one position;

Fig. 5 is a similar view as seen from a position 180° removed; and

Fig. 6 is a cross section taken at 6—6 of Fig. 1.

I claim:

The ornamental design for a finger ring, substantially as shown and described.

LUCIEN S. BURRI.
